ELECTRICAL CONNECTOR

Milton Cohen, Brooklyn, N. Y.

Application October 23, 1953, Serial No. 27,296

Term of patent 3½ years

(Cl. D26—1)

To all whom it may concern:

Be it known that I, Milton Cohen, a citizen of the United States, residing at Brooklyn, in the county of Kings and State of New York, have invented a new, original, and ornamental Design for an Electrical Connector, of which the following is a specification, reference being had to the accompanying drawing, forming part thereof.

In the drawing:

Fig. 1 is a top perspective view of an electrical connector, showing my new design; and

Fig. 2 is a bottom perspective view thereof taken from the opposite end of the connector as shown in Fig. 1.

I claim:

The ornamental design for an electrical connector, as shown.
